as at the present and in the future, and every improvement, modification, and variation which may be suggested and made in the structure herein described, in any manner, without departing from the spirit and scope of the same, and without giving up the main idea thereof, is intended to be secured as far as the law permits, to the inventor in respect of the same.

UNITED STATES PATENT OFFICE

2,668,332

SHINGLE CORNER CONSTRUCTION

John D. Roth, North Wildwood, N.J.

Application February 23, 1951, Serial No. 212,408

2 Claims. (Cl. 20—5)

1

This invention relates to improvements in building construction and more particularly to improvements in angle pieces for asbestos siding shingles.

It is an object of the invention to provide a reinforced asbestos cornerpiece for use with asbestos shingles which are applied as a siding on building construction.

Another object is to provide as an article of manufacture or prefabricated structure, an angular corner section made of the same material and texture as a shingle siding whereby a more substantially weatherproof and longer lasting corner structure is produced, as well as a shingle siding construction which is more pleasing in appearance than conventional building structures comprising asbestos shingle sidings.

Another object of the invention is the provision of a one-piece asbestos siding shingle cornerpiece of varying length, width and thickness, and having a smooth or hardwood-grain finish, and in any desired color.

Another important object of the invention comprises a unitary asbestos corner piece which is reinforced with a substantially square or rectangular shape cross-section integral portion positioned directly in the corner and contiguous with each leg portion of the L-shaped shingle.

Still another object of the invention is the provision of a corner sheathing construction which is cut back on a line with the front edges of the corner post frame structure to form a right angular shaped recess to receive felt paper and the reinforcing strip of the asbestos cornerpiece siding shingle.

Still another improvement feature of the invention comprises the expedient of providing an asbestos corner piece shingle for fabricating outside or inside building structures and wherein such outside and inside corner construction can be installed before the remainder of the siding shingles are applied, thus facilitating the fabrication of the building structure.

Various other objects and advantages will be apparent as the invention is described in more detail.

While it has been proposed, heretofore, to provide asbestos cement siding cornerpieces formed from a moulded body of asbestos cement of V-shaped contour in cross-section which is applied to a corner post of a building, the asbestos cornerpiece of the present invention provides an improved structure thereover. An important improvement feature comprises the provision of an integral reinforcing portion along the corner of

the shingle and which facilitates holding and holding in place during the application of the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

Another feature of the invention is the provision of a cornerpiece which is interlocked with the shingle.

2

the asbestos angle piece which is adapted to fit snugly into a recess provided in the sheathing contiguous with the corner of the building. This corner construction permits interlocking of the corner shingle piece with the sheathing and felt paper backing so that a more substantial corner construction is provided than when using ordinary or L-shaped corner shingles. Moreover, the unitary one-piece asbestos shingle of the present invention, which is provided with a reinforcing filling at the corner of an asbestos L-shaped cornerpiece, is a decided improvement over metal-type cornerpieces which are in general use, as such metal corner pieces tend to discolor and corrode, spoiling the appearance of the building.

Although the novel features which are believed to be characteristic of this invention will be pointed out more particularly in the claims appended hereto, the invention itself as to its objects and advantages and manner in which it may be constructed and applied to new and old building structures, may be better understood by referring to the following description taken in connection with the accompanying drawings in which a specific embodiment thereof has been set forth for purposes of illustration.

In the drawings:

Figure 1 is an elevational view of an outside corner of a building embodying cornerpiece shingle structure of the present invention, the siding portion of the building being shown broken away;

Figures 2 and 3 are perspective views of a right and left cornerpiece, respectively, which is constructed in accordance with this invention to provide for staggered joints in build up corner structure;

Figure 4 is a side elevational view of a building structure and illustrating an outside and inside corner construction embodying the cornerpiece of the invention, the inside corner structure being shown broken away and partly in section;

Figure 5 is a plan view in section and taken substantially on the line 5—5 of Figure 5 and looking in the direction of the arrows; and

Figure 6 is a fragmentary sectional view taken through the outside corner structure illustrated in Figure 5 and substantially along the line 6—6 of said figure.

Referring to the drawings more in detail and wherein like reference characters refer to like parts throughout the several views, in Figure 1 there is illustrated a portion of an outside corner

building structure having asbestos siding mem-

bers 10 which are provided along the corner with right and left asbestos shingle corner pieces 12 and 13, respectively, which embody the novel structural features of this invention. The corner-pieces are suitably moulded in one-piece and may be made in any suitable color and in varying widths and lengths and with a smooth or wood-grain finish on outer surface, as desired. A principal feature of construction of the asbestos corner piece, in accordance with this invention, is the provision therein of a reinforcing integrally moulded internal rib portion 15, as illustrated in Figures 2 and 3 which is square-shaped in cross section, as indicated at 16, and fills in the corner portion contiguous with the corner line 18 formed by the intersection of the leg portions 21 and 22.

The L-shaped asbestos corner piece is preferably molded in the form of right and left hand corner pieces, as illustrated at 12 and 13 in Figures 2 and 3, respectively. Each is of like construction except that a corresponding leg member of the L-shaped asbestos shingle is made wider in one instance than the other and its relative position with respect to the corner line 18 is reversed, whereby when the corner piece is applied to a corner structure the jointure, as shown at 25 in Figure 1, of contiguous courses is staggered. Further, the reinforcing square-shaped section 15 terminates short of the end of the corner piece in order to provide an overlapping portion 28. Suitable apertures 30 also are provided in the lower portion of the leg members for receiving nails or the like securing means, to fasten the corner piece to the sheathing 32.

An important improvement in asbestos shingle-type construction also is provided utilizing the asbestos corner piece of this invention by virtue of the interlocking of the sheathing with the corner piece. As illustrated in Figures 4 and 5, by cutting the sheathing back, as at 35, so as to form a right angle opening or recess of the proper dimensions to receive the square-shaped integral reinforcing portion 15 of the asbestos corner piece 13, the same is made to fit snugly in place. The felt or building paper lining 38, which is usually applied over the sheathing 32 is lapped over and into the recessed corner section 35, and is securely held in place by the square-shaped reinforcing portion 15 which is fitted into the cutout section and contiguous with corner edges of the sheathing. The construction described permits the siding shingles 10 to butt evenly against the edges of the asbestos corner piece, as shown at 25 in Figure 5. In this manner a corner structure is provided having a neat appearance and a first class job is achieved.

Where the corner piece of the invention is to be installed on an inside corner, as illustrated in Figures 4 and 6 at 40, the integral reinforcing portion 15 of the corner piece will be turned outwardly and the corner piece installed upside down, being suitably nailed to a supporting back wall 42 or wood nailing strip means.

It will thus be apparent that the present invention provides a molded unitary corner piece which has particular utility as an asbestos shingle for installation along outside or inside of building corners, and such as may be fabricated of asbestos shingles or siding pieces. Further, while the invention is especially applicable to moldable asbestos building material, it is obvious the corner piece of the invention may be made of other material suitable for building purposes and wherein like problems are presented as with asbestos shingles.

While certain novel features of the invention have been disclosed and are pointed out in the annexed claims, it will be understood that various omissions, substitutions and changes may be made by those skilled in the art without departing from the spirit and scope of this invention.

Having described the invention, what is claimed as new is:

1. A prefabricated unitary asbestos corner piece shingle for a building comprising a pair of elongated flange members intersecting at substantially right angles, a reinforcing integral-rib portion shorter than said flange members and throughout its length filling in the corner formed by said intersecting flange members, said integral reinforcing rib portion being substantially square in cross section to fit in a V-groove formed in a corner of the building.

2. In a siding retaining and corner protecting means, a supporting wall having sheathing forming at contiguous ends thereof an angular recess arranged along the corner line of said wall, an upstanding integral body having elongated flange portions intersecting substantially at right angles, a reinforcing rib portion integral with and shorter than said flange portions and throughout its length filling the right angular corner formed by said intersecting flange portions, said reinforcing rib portion being substantially square in cross section and fitting in said recess.

JOHN D. ROTH.
